BLACKBOARD CONSTRUCTION

Niels C. Sorensen, Detroit, Mich.

Application November 16, 1931, Serial No. 575,263

9 Claims. (Cl. 35—65)

This invention relates generally to building construction and relates particularly to the construction of display boards such as blackboards and bulletin boards employed in classrooms, conference rooms, laboratories and elsewhere.

An object of the invention is to provide a more economical plan of construction for blackboards and bulletin boards than has heretofore been employed and one which will not require the employment of numerous blackboard casing and molding elements projecting outwardly from a building wall in such manner as to be not only displeasing in appearance to ordinary persons but relatively unsanitary because of the facility of such elements for collecting dust ordinarily removed therefrom only at infrequent intervals.

Another object of the invention is to provide for the construction of blackboards, bulletin boards, etc., conforming to more or less modernistic principles of design of simplified or unitary construction easily and quickly assembled which are more suitable to the contracting and subcontracting methods now generally employed in building construction.

Another object of the invention is to employ sheet metal casing elements in the construction of blackboards and other similar articles which can be restricted in application to a region in a wall which is substantially within the exterior surface thereof and which metallic and other elements can be employed not only for defining the region occupied by such blackboards, etc. and for restricting plastering and the like therefrom but for retaining such blackboards, etc. in position within the wall.

Heretofore it has been customary to nail or otherwise secure preferably wood or other suitable members to a rough and unplastered wall not only to define the region in which a blackboard, for example, was to be installed but to receive nails from or otherwise to support molding or casing members projecting outwardly beyond the finished wall and employed for the purpose of retaining the blackboard in position and for covering from view the unsightly wood members and the adjacent edges of the plastering.

The plan of construction embracing this invention proposes to do away entirely with such outwardly projecting casing or molding elements and to so modify the construction of the wood members heretofore employed as by employing sheet metal members therewith as to accomplish all of the purposes which such construction demands.

For a better understanding of the invention, reference may now be had to the accompanying drawing forming a part of this specification, in which—

Figure 1 is a fragmentary side elevational view 5 of the interior of a room containing a blackboard and bulletin board constructed in accordance with the principles of this invention;

Fig. 2 is a transverse sectional view of said wall taken substantially on line 2—2 of Fig. 1; 10

Fig. 3 likewise is a transverse sectional view 15 of said wall illustrated by Fig. 1 taken substantially on line 3—3 thereof;

Fig. 4 is a fragmentary transverse sectional view taken substantially on line 4—4 of Fig. 1; 15

Fig. 5 is a view similar to Fig. 4 taken substantially on line 5—5 of Fig. 1;

Fig. 6 is a fragmentary transverse sectional view 20 of the wall illustrated by Fig. 1 and is taken substantially on line 6—6 thereof.

Referring particularly to the figures of the drawing, a wall 10 of any room or building in which a blackboard or bulletin board embracing the principles of this invention is employed, comprises a supporting wall structure 11 which, in the 25 present instance, consists of a vertically disposed concrete slab, although it may consist in other instances of wood, tile, brick, stone, channel and metal lath, gypsum, or any other material suitable for the construction of the walls of buildings. 30

During the construction of the wall 11 blocks 12 of wood or other suitable material are inserted therein at regular intervals (see Figs. 2, 4 and 5) and to which blocks various kinds of wall fixtures may be attached. 35

In the present instance a plurality of the blocks 12 are so inserted in the concrete wall 11 as to support a frame 13 defining an opening or region or recess 14 in which a blackboard 16 and a bulletin board 17 are located. 40

In general the frame 13 comprises a pair of vertically disposed and spaced side sections 18 and 19, spaced top and bottom sections 21 and 22 respectively, and an intermediate section 23.

The upper section 21 (see Figs. 1 and 2) comprises a pair of sheet metal members 24 and 26 between which a wooden or other suitable member 27 is secured. The sheet metal member 26 which is disposed between the wooden member 27 and the concrete wall 11, has an outwardly projecting 50 flange along the upper edge thereof, the height of which determines the thickness of the inner finish coating or plastering 29 of the wall and defines the upper extremity of the region in which the blackboard 16 and billboard 17 are installed. 55

Referring to the upper portion of Fig. 2, the outer sheet metal member 24 is provided with a similar flange 31 except that the latter projects inwardly along the inside surface of the flange 28. The wooden member 27 and the sheet metal member 26 are both secured to the wall 11 by screws 32 extending therethrough and into the wooden blocks 12 forming an integral part of the wall 11, while the outer sheet metal member 24 is secured to the wooden member 27 by screws 35. Adjacent the lower or inner edges thereof the sheet metal members 24 and 26 are deflected toward each other, as indicated at 33, to provide supports or supporting flanges 34 and 36 between 15 which the upper edge of the bulletin board 17 is confined.

The bulletin board 17 is constructed of any suitable relatively soft material in which pins or tacks can be readily inserted and removed, for 20 example, such as cork, paper board, wood, etc.

The supporting flange 34 at its lower edge is provided with an upwardly turned flange portion 37 behind which hooks 38 are removably supported at desired intervals.

In the lower portion of Fig. 2, the intermediate section 23 between the bulletin board 17 and the blackboard 16 is shown which likewise comprises an inner sheet metal member 39, a wooden or other suitable member 41 and an outer sheet metal member 42. The inner sheet metal member 39 and the wooden member 41 are secured rigidly to the wall 11 with the inner sheet metal member 39 between the wooden member 41 and the wall by screws 43 projecting through both members and 35 into blocks 12 hereinbefore referred to. The edge of the inner sheet metal member 39 is offset, as indicated at 44, to provide a supporting flange 46 similar to the flange 36 of the sheet metal member 26 and cooperating with said flange 36 to support the rear of the bulletin board 17. The outer sheet metal member 42 extends over the adjacent edges of the bulletin board 17 and the blackboard 16 and there is provided with inwardly extending flanges 47 and 48 which abut the front surfaces 45 of the bulletin board and blackboard and assist in retaining such elements in position. Screws 49 are employed for retaining the front sheet metal member 42 in position against the front surface of the wooden member 41.

The blackboard 16 is constructed of slate or of such composition boards as those embracing wood pulp, asphalt, concrete, asbestos or other materials suitable for the purpose.

As illustrated in Fig. 3, the lower extremity of the region or recess 14 is defined by a relatively wide wooden member 51 which is secured against the wall 11 by screws 52 extending through such member and into the blocks 12. A chalk trough 53, preferably formed from a single sheet metal 55 of any suitable character into a suitable section such as that indicated in Fig. 3, is secured to the front surface of the wooden member 51 by screws 54 and 56 projecting through the vertically disposed back or plate portion of the trough and into the member. A lower edge 57 of said back portion of the trough 53 projects downwardly to such an extent as to cover the adjacent edges of the wooden member 51 and the inside finishing coating 29 of the room. The upper edge 58 of said 60 back portion comprises an inwardly extending flange 59 which abuts the front surface of the blackboard 16 adjacent the lower edge thereof and hence cooperates in maintaining the blackboard in position within the wall. Daubs of concrete, plaster, or other suitable material, indi-

cated at 61, cooperate with each other to maintain the blackboard 16 outwardly with respect to the wall 11 and against the edges of the front sheet metal member 42 and the portion 59 of the chalk trough 53.

The side section 18 (see Fig. 6) comprises an inner sheet metal member 62, an outer sheet metal member 63 and an intermediate wooden or other suitable member 64 which is secured to the wall 11 on the outer surface of the inner member 62 by screws 66 projecting therethrough and into the blocks 12. The outer sheet metal member 63 is secured to the outer surface of the wooden member 64 by screws 67. The inner sheet metal member 62, like the inner sheet metal member 26, is provided with an outwardly projecting flange 68 adjacent one edge thereof which defines one side of the region 14 and retains the finishing coating 29 of the room in position during the hardening process of the latter. The corresponding edge of the sheet metal member 63 is provided with an inwardly extending flange 69 which projects along the inner surface of the flange 68.

The opposite edge of the outer sheet metal member 63 is provided with a portion extending outwardly over the adjacent edge of the blackboard 16 and having an inwardly projecting flange 71 which abuts the front surface of the blackboard and tends to retain the latter in position.

In the region adjacent the bulletin board 17 the flange 71 of the outer sheet metal member 63 there engages the bulletin board rather than the blackboard and likewise serves to retain that element in position.

The inner sheet metal member 62 in Fig. 6 also may be provided in such region with an inwardly extending supporting flange (not shown) but similar to the flanges 36 and 46 disclosed by Fig. 2. This flange may be employed for supporting the rear surface of the bulletin board 17 although such is not absolutely necessary in view of the flanges for this purpose projecting from the sheet metal members 26 and 39.

As illustrated in Fig. 4, the side section 19 is 45 not exactly like the side section 18 in certain constructional details because of its employment at a corner in the wall 11 defining one edge of an opening 73 in which a bookcase or other fixture or furnishing element 75 is inserted. Of course 50 the section 19 embraces substantially the same constructional elements as the section 18 although in the former they are arranged somewhat differently to accommodate this variation in room construction.

However, as illustrated in Fig. 4, the section 19 comprises an inner sheet member 74 having a wooden or other suitable spacing member 76 secured thereon by screws 77 projecting through the members into blocks 12 in the wall 11. The outer surface of the member 76 is covered by a sheet metal member 78 which is secured to the member 76 by screws 79. The inner sheet metal member 74 is provided with a supporting flange 81 for the rear of the bulletin board 17 although, as hereinbefore indicated, such flange may be eliminated on the end section if desired. On the opposite edge thereof the inner sheet metal member is provided with an outwardly projecting flange 81 which extends, in this instance, along 70 the inner surface of an inwardly projecting flange 82 formed on one edge of the outer sheet metal member 78. Inasmuch as the outwardly projecting flange 81 is not required to support the finishing coating 29 of the room, the outer edge 75

thereof may be cut off, as indicated at 83 in Fig. 4, or the entire inner sheet metal member 74 may be eliminated if desired, as indicated in Fig. 5. In either instance, however, a molding 5 such as that illustrated at 84 may be employed to cover the space between the rear edge of the flange 82 and the front corner surface of the bookcase 75. The opposite edge of the front sheet metal member 78 extends outwardly over the blackboard 16 and the bulletin board 17 and is there provided with an inwardly projecting flange 86 which retains such elements in their proper position.

While in all figures of the drawing the sections 18, 19, 21, 22 and 23 have been indicated as secured rigidly to the wall 11 by employing the blocks 12, it is to be understood that the latter may be entirely eliminated simply by drilling holes in the material of the wall and employing 20 therein toggle bolts, ordinary bolts or nails (not shown) of well known construction rather than screws and blocks as illustrated.

In assembling a building embracing a bill board and blackboard construction such as that illustrated herein, the frame sections 18, 19, 21, 22 and 23 are secured rigidly to the supporting or main wall 11 in any suitable manner but in such relation as to define a region or opening of suitable dimensions for the reception of the blackboard and bill board elements and this is done before the inside coating 29 or plastering of the room is applied. When workmen later apply such coating they simply cover the inner walls of the building therewith up to a depth equal to the 35 height of the flanges projecting outwardly from the inner sheet metal members employed in all of the various sections but not within the region 14 therein. The blackboard 16 and the cork board 17 then are placed in their respective positions; 40 the cork board 17 being merely placed against the inner supporting flanges of the inner sheet metal members of the sections of the frame, and the blackboard being placed upon the upper edge of the wooden frame member 51 and pressed 45 slightly against daubs of freshly mixed plastering material or cement which are placed on the wall 11 before the blackboard is disposed in position. The outer sheet metal members and the chalk trough then are secured in position by 50 tightening their respective attaching screws and the structure thus assembled is ready for service.

It is to be understood that the blackboard and bulletin board 16 and 17 can be employed in separate frames if desired rather than as a composite unit as illustrated.

Although, for the purpose of illustration, only a particular form of the invention has been disclosed in detail, it is to be understood that the invention is not so limited but may be embraced 60 in numerous other structures within the spirit of the invention and the scope of the appended claims.

I claim:

1. A building construction comprising a wall 65 having a recess therein, a board disposed within said recess for displaying visible characters upon the front surface thereof and sheet metal frame means secured to the bottom of said recess and substantially flush with the outer surface of said 70 wall for securing said board in a position within said recess of relatively close proximity to the plane of said outer surface.

2. A building construction comprising a plastered wall having a substantially blind recess 75 therein, a plurality of inner frame members dis-

posed in the bottom of said recess around the margin thereof and each coextensive with an edge of said recess, said frame members having outwardly turned edges terminating at the outer surface of said wall, a plurality of spacing members secured on said frame members, said spacing members having a thickness slightly less than the depth of said recess, a board disposed within said recess approximately flush with said outer surface for the display of visible characters thereon and a plurality of outer frame members coextensive with said inner frame members covering the edges of said board and the outer surfaces of said spacing members and being spaced from the bottom of said recess by said spacing members. 10 15

3. A board construction comprising a pair of spaced sheet metal members each having a flange in superposed contacting relation to the corresponding flange of the other member at corresponding edges thereof and each having a flange 20 adjacent the opposite edge in spaced and parallel relation to the corresponding flange on the other member, a display board confined between said flanges and a member received between and contacting opposed faces of said sheet metal members 25 for spacing said sheet metal members, said display board and spacing member being of relatively different thickness.

4. A blackboard frame member comprising a pair of sheet metal angle members arranged in 30 face-to-face relation with the feet of the angles contacting and overlapped with respect to each other whereby to form an inwardly opening channel for the reception of a blackboard, the margin of the leg of the outer angle member being re- 35 versely bent whereby to form a channel for the removable reception of hook members.

5. In a building construction comprising a plastered wall having a recess therein, a board disposed within said recess with its front face inwardly and slightly offset with respect to the front face of said wall for displaying visible characters thereupon, means secured to said wall independently of the front face thereof and substantially flush with said front face aiding in 40 the positioning of said board and serving as a guide for the depth of plaster during construction of said wall, and means substantially flush with said wall for securing said board to said wall.

6. A building construction comprising a wall 50 having a recess therein, a board within said recess for displaying visible characters upon the front surface thereof and a plurality of sheet metal frame members marginally embracing opposite face surfaces of said board and securing the same 55 in position, the front surfaces of said frame members being substantially flush with the outer surface of said wall and approximately flush with the front surface of said board.

7. A wall construction comprising a substantially imperforate inner supporting portion and an outer finishing covering of plaster of the usual thickness therefor, said finishing covering having an opening therein, a board disposed within said opening and a supporting frame secured to said 65 supporting wall and of substantially equal depth as compared with said finishing covering whereby the outer face of said frame is substantially flush with the outer face of said finishing covering and the outer face of the board is approximately flush 70 with said face of the finishing covering, said supporting frame having said board secured thereto.

8. A building construction comprising a wall having a recess therein, a board disposed within said recess for displaying visible characters upon 75

the front surface thereof and frame means substantially flush with the outer surface of said wall and adapted to secure said board within said recess in a fixed position relative to the depth of 5. said recess approximately flush with said outer surface.

9. In a building construction, wherein a wall has a recess therein, and two boards are disposed within said recess edgewise adjacent each 10. other for displaying visible characters thereon, the combination, a supporting frame member

substantially flush with the wall surface and intermediate and overlapping the adjacent edges of said boards for securing said boards relative to the wall, and other frame members flush with the wall adjacent and overlapping the remaining edges of said boards and embracing opposite face surfaces thereof for securing same relative to the wall, the one of said frame members adjacent the lower edge of said remaining edges being further formed to provide a crayon and eraser trough. 10. 5

NIELS C. SORENSEN.
